WINDLASS COMPANY, OF BATH, MAINE, A CORPORATION OF MAINE.

ELECTRIC INDICATING AND SIGNALING SYSTEM.

Application filed October 26, 1923. Serial No. 670,972.

Our present invention relates to an improved form of electrical apparatus for transmitting signals or indications, and is hereinafter described as embodied in a ship's telegraph, for which it is particularly well adapted, though not limited to such use.

The invention aims to provide an electric transmission system which shall be free from contacts, which latter are objectionable in ship's installations and similar positions where they are liable to corrosion from the moist salt air.

Another object is to provide such a system adapted to be operated by alternating currents now so generally used on shipboard.

Another object is to provide a system by which a large, or practically unlimited number of indications may be transmitted, and in which a loud sounding device or audible signal may be included, so arranged as to continue sounding until the signals have been repeated back to the sending station, thus indicating to the sending station that the signals have been observed, and ensuring the attention of the receiver being called to the signals under noisy conditions surrounding the receiving instrument.

With these and other objects in view the invention includes the novel features hereinafter described, the nature and scope of the invention being defined and ascertained by the claims appended hereto.

An embodiment of the invention is illustrated in the accompanying drawings, in which:—

Figure 1 is a diagrammatic view showing the parts in neutral or stop position.

Fig. 2 is a similar view with the signal transmitting handle set at full speed ahead, and

Fig. 3 is a view similar to Fig. 2 with the reply handle shown as having been turned for transmitting the reply to the sender.

In describing the wiring as diagrammatically shown, it is to be understood that polarities have only instantaneous values in A. C. circuits. They are therefore, indicated in the drawing only for the ahead angle of the transformer secondary as an aid in tracing and understanding the relation

between the holding and pulling magnets of the polarized selectors and indicators.

Our improved apparatus or system comprises three main instrumentalities, to wit, a transmitter T located at the signal sending station, a receiver R located at the receiving station, and a polarized selector relay PSR arranged to actuate one or more sounding devices located at the receiving station, these being connected by constantly closed A. C. circuits as hereinafter more fully described.

The transmitter and receiver are duplicates of each other, and each includes a variable ratio transformer and a polarized indicator, the transmitting transformer being designated TT and the receiving transformer RT, while the transmitting indicator is designated TI and the receiving indicator RI.

Each transformer comprises a stationary primary (P or P') and a movable secondary (TS or RS) capable of being rotated through suitable connections such as the conventionally shown shaft or rod and gear connections from an operating handle. In the case of the transmitting transformer, the transmitting handle is designated TH and the operating connection G', G², G³, G⁴, the shaft or rod connections being broken away for convenience of illustration. The handle for operating the receiver secondary is designated RH and the connections G⁹, G¹⁰, G¹¹ and G¹².

Associated with each operating handle is a dial bearing indicating characters according to the nature of the signals to be transmitted, and a cooperating pointer, as shown conventionally in the drawings.

The primaries P and P' of the transmitting and receiving transformers are connected in parallel by lines or conductors L' and L² with the main AC supply conductors A' and A². Line L² is also connected with one terminal of secondary TS, the other extremity of which is connected with what may be termed transmitter common line TC, which in turn is connected with the polarized selector relay PSR and receiving indicator RI in the manner hereinafter described. In a similar manner the line or

conductor L' is connected with the receiver secondary RS which in turn is connected to polarized selector relay PSR and transmitting indicator TI as also hereinafter more fully described.

The indicators TI and RI and the polarized relay PSR each comprises a series of annularly arranged electro-magnets co-operating with an armature vane (V , V' or V^2).

- 10 Referring first to indicator TI the magnets are shown as six in number and their coils are designated C^{11} to C^{16} inclusive. Coils C^{11} and C^{12} are connected with line RC and also by independent connections with coils C^{13} and C^{14} , which latter are connected to conductor L' . Coils C^{15} and C^{16} are connected in series with conductors L' and L^2 through an interposed impedance so designated on the drawings. Vane V has its 20 pivot connected by suitable operating connections with an indicating pointer TP , the connections illustrated conventionally comprising shaft or rod and gear connections designated G^{13} to G^{16} inclusive.
- 25 In a similar manner coils C' and C^3 of indicator RI are connected to conductor TC and by independent wires to coils C^2 , C^4 respectively, which in turn are connected with line L^2 . Coils C^5 and C^6 are connected in 30 series with line L' and through a choke coil with line L^2 , using preferably the same return wire as coils C^2 and C^4 . Vane V' is connected by similar connections (G^5 to G^6 inclusive) with indicating pointer RP .
- 35 In polarized selector relay PSR coils C^8 and C^9 are connected with conductor L^2 , coil C^8 being connected with coil C^7 which in turn is connected with line TC^2 which is a branch from line TC , while coil C^9 is connected to coil C^{10} which latter is connected to conductor L' . Coil C^{13} is likewise connected to line L' and also to coil C^{17} which in turn is connected to branch RC^1 of line RC . The armature vane V^2 carries a switch arm S^1 40 which cooperates with opposed contacts S^2 , S^3 to close a circuit through sounding means such as a horn H or bell B , or both, on movement of the armature vane in either direction.
- 45 Figure 1, as hereinbefore stated, shows all moving parts in the neutral or stop position. The primaries of the variable ratio transformers TT and RT , and the coils of the polarized indicators T^1 and R^1 that are in phase with the primaries, are constantly 50 excited, these circuits being indicated by the arrows. The secondaries of both transformers TS and RS , being at right angles to the primaries, have no pressures induced in their circuits, and hence no direction arrows 55 are shown.

Turning the handle TH of transmitter T to, for example, full speed ahead, as shown in Fig. 2, through the connections described, operates or moves the secondary TS of transmitting transformer TT . As the secondary

output varies with its angularity and its instantaneous current direction or phase relation to the primary is determined by the direction in which the secondary is shifted from its neutral position, turning the secondary clockwise from its neutral position 70 sends current as indicated by the arrows Fig. 2 over the secondary circuit TC to the polarized selector indicator RI , through magnet coils C^1 and C^2 in series, and C^3 and C^4 75 in parallel to line L^2 and back to secondary TS . The magnitude of this current, and of the flux set up in coils C^1 to C^4 , is proportional to the extent to which the secondary is turned. Magnet coils C^5 and C^6 are 80 connected in series directly across the line wires L' , L^2 . These magnets, as will be understood from the foregoing, give polarity to the armature vane holding it in central or stop position when coils C^1 , C^2 , C^3 , C^4 are 85 not energized, and their intensity or pull may be regulated by adjustable air gaps in the magnetic circuit, or impedance coils, or both in the manner well understood by those skilled in the art. When the handle TH has 90 been turned in a clockwise direction the vane of indicator RI turns clockwise to an equal degree under the influence of the resultant magnetic field, due to the deflection or shifting of the flux from the polarizing coils C^5 95 and C^6 by the action of the coils C^1 , C^2 , C^3 , C^4 and the relative indicating angle is imparted to the pointer RP through the connections described, the position of full speed ahead being illustrated as merely an example.

Wires TC^2 and L^2 are in multiple with the secondary circuit TC and L^2 of transformer TT and are connected to magnet coils C^7 and C^8 of polarized selector relay PSR . When 105 the handle TH is turned as above described, coils C^7 and C^8 are excited and flux from these coils deflects the vane V^2 and causes switch arm S' to close the circuit at S^2 through the sounding device.

In Fig. 2 the handle RH not being turned, shows that the order has not been repeated back, and hence no direction arrows appear in the RC secondary circuit.

To send back such reply, the handle RH is 115 turned to an equal degree in a clockwise direction, say to full speed ahead and corresponding movement is imparted through connections G^9 to G^{12} to secondary RS and induced current flows therefrom through 120 secondary circuit RC to indicator TI through magnet coils C^{11} and C^{12} in series and C^{13} , C^{14} in multiple and back to secondary RS by common return line L' . Flux from these magnets, deflecting the path of the flux from magnets C^{15} , C^{16} , to an angle corresponding to the angle to which the receiver handle has been moved, the vane follows the path of the flux and turns to the right, transmitting motion through the connections G^{13} to G^{16} to 130

pointer TP which stops at the proper position, in this instance in the full speed ahead position directly in line with handle TH. At the same time, current from the secondary RS over secondary circuit RC and L' divides at RC¹ and part passes to magnet coils C¹⁷ and C¹⁸ and thence back to secondary RS. As the angularity of secondaries TS and RS is the same, the flux from magnets C¹⁷ and C¹⁸ will equal or balance the flux of magnets C⁷ and C⁸ and the vane V² will be attracted to neutral position by magnets C⁹ and C¹⁰, causing switch arm to break the circuit and the sounding device to be discontinued.

An astern order and reply will give similar results except that the secondary and armatures will turn to the left or in a counter-clockwise direction and the instantaneous direction of the current and phase relations in the secondary circuits will be opposite or reversed.

While we have described our invention in detail as embodied in a ship's telegraph, it is obvious that it is capable in whole or in part, for use in a great many situations. For example, it is capable of being used as an angle indicator to indicate the angle to which any moving part is moved, as for instance a ship's rudder, as in such case it is only necessary to use a transmitter and receiver, and have the secondary connected to be moved in unison with the rudder, when of course, the movement of the receiver armature would indicate the angle to which the rudder was moved. In such case, the receiver armature or vane could be operatively connected to any suitable pointer cooperating with a dial graduated to indicate degrees of inclination.

If the operating handle of the secondary were replaced by a rotary element capable of complete rotation in either direction, such as a continuously rotating shaft, the receiver, armature, vane and pointer would oscillate back and forth once every revolution and this motion would actuate any mechanical counter, or the pointer oscillations could be counted for a period, giving the revolutions for this period.

The system may also be used for indicating the number of revolutions per minute of a shaft or other rotating element, by any suitable arrangement by which the rotor would be oscillated or deflected to a degree corresponding to the amount of outward movement of the balls or weights of a centrifugal governor, the revolutions per minute being indicated by a pointer operated by the receiver and traveling over a suitably graduated scale.

It will be understood that gears are introduced between the handle TH and secondary TS because 90° would be the maximum turn of secondary TS and 50° is con-

venient. 30° is shown as the deflection of the indicator vane and is found by experiment, the choke or induction coil being inserted in circuit for close calibration, as increasing or decreasing the pressure and current in the holding magnets regulates the deflection of the vane. Gears must also be introduced to move the pointer RP 144° to agree with the handle of the transmitter. The ratios mentioned are not important and both electrical and mechanical ratios would be designed to meet requirements.

It will also be understood that we do not limit ourselves to the particular arrangement of receiver coils or magnets for producing the variable flux in the receiver, as these may be arranged and connected in various ways; or if desired, part of the flux could be furnished by substituting a properly connected wound armature for the vane shown and described. For instance, in indicator T¹, we might connect magnets C¹¹, C¹², C¹³, and C¹⁴ to line L¹ and L², so that they will provide the holding field for a vane or armature instead of C¹⁵ and C¹⁶, and connect C¹⁵ and C¹⁶ to L¹ and RC making these magnets furnish the actuating or pulling flux, or a wound armature could be substituted for a vane, dispensing with magnets C¹⁵ and C¹⁶. Also with properly designed pole pieces, the poles of magnets C¹¹ and C¹⁸, and C¹² and C¹⁴, might be joined or substituted by single magnets.

The term "polarized", as employed in this specification, is not to be understood as implying the use of permanent magnets, but is intended to mean an arrangement in which a soft iron armature or vane is normally maintained in a definite position by means of constantly energized holding coils or the like.

Having thus described our invention, what we claim is:—

1. In an electrical transmission of the class described, the combination with two stations each comprising a transmitter and a receiver, of two main and two auxiliary conductors constituting the sole connection between said stations, a source of alternating current connected with said main conductors, each transmitter including means for setting up in a circuit comprising one of said main and one of said auxiliary conductors alternating currents variable at will in intensity, and each receiver comprising a plurality of energizing windings, and a pivoted magnetic element so located as to be influenced directly by the flux from said windings, whereby said element may be caused to take up any one of a number of different angular positions in response to the relative variations of the currents flowing through the several conductors, as produced by the operation of the respective transmitters.

2. In an electrical transmission of the class described, the combination with two stations each comprising a transmitter and a receiver, of two main and two auxiliary conductors constituting the sole connection between said stations, a source of alternating current connected with said main conductors, each transmitter including means for setting up variable currents in a circuit comprising one of said main and one of said auxiliary conductors, and each receiver comprising a plurality of energizing windings, and a pivoted magnetic element so located as to be influenced directly by the flux from said windings whereby said element may be caused to take up any one of a number of different angular positions in response to the relative variations of the currents flowing through the several conductors, as produced by the operation of the respective transmitters.
3. In an electrical transmission of the class described, the combination with two stations each comprising a transmitter and a receiver, of two main and two auxiliary conductors constituting the sole connection between said stations, a source of alternating current connected with said main conductors, each transmitter including means for setting up variable currents in a circuit comprising one of said main and one of said auxiliary conductors, and each receiver comprising a pivoted magnetic element and means for causing the same to take up any one of a number of different angular positions in response to changes in magnetic flux due to the relative variations of the currents flowing through the several conductors, as produced by the operation of the respective transmitters, and an audible signal device at one of said stations, means controlled by the variable currents set up by the transmitter at the other station and traversing some of said conductors for putting said signal in operation, and means controlled by the variable currents set up by the transmitter at its own station for stopping the operation of said device.
4. In an electrical transmission of the class described, the combination with two stations each comprising a transmitter and a receiver, of two main and two auxiliary conductors constituting the sole connection between said stations, a source of alternating current connected with said main conductors, each transmitter including means for setting up variable currents in a circuit comprising one of said main and one of said auxiliary conductors, and each receiver comprising a movable element and electromagnetic means for moving the same in response to the relative variations of the currents flowing through the several conductors, as produced by the operation of the respective transmitters, an audible signal device associated with one of said receivers, and means operable over some

of the same conductors whereby said audible signal is automatically sounded upon the operation of said receiver, and automatically silenced after the operation of the other receiver to a corresponding indication.

70

5. In an electrical transmission of the class described, the combination with two stations each comprising a transmitter and a receiver, of two main and two auxiliary conductors constituting the sole connection between said stations, a source of alternating current connected with said main conductors, each transmitter comprising a stationary primary in circuit with said main conductors, and a secondary circuit with one of said main and one of said auxiliary conductors, and movable to vary its relation to the primary, and each receiver comprising a plurality of energizing coils and a movable magnetic armature, some of said coils being in circuit with said main conductors and others in a circuit including one of said auxiliary conductors and one of said main conductors, whereby movement of the secondary of the transmitter at one station varies the relation of the currents flowing through the coils of the receiver at the other station, and causes the armature thereof to shift its position.

6. In an electrical transmission of the class described, the combination with two stations each comprising a transmitter and a receiver, of two main and two auxiliary conductors extending between said stations, a source of alternating current connected with said main conductors, each transmitter comprising a stationary primary in circuit with said main conductors, and a secondary in circuit with one of said main and one of said auxiliary conductors, and movable to vary its relation to the primary, and each receiver comprising a plurality of energizing coils and a movable magnetic armature, some of said coils being in circuit with said main conductors and others in a circuit including one of said auxiliary conductors and one of said main conductors, an audible signal device, and means for controlling the same, said means including a movable magnetic armature and a plurality of controlling coils, some of which are in circuit with said main conductors, and some of which are in other circuits comprising said auxiliary conductors as well, whereby, movement of the secondary of a transmitter serves to vary the relation of the currents flowing through the coils of both the receiver at the other station and said audible signal controlling means, so that both armatures shift their positions.

7. In an electrical transmission system, and in combination, two stations each comprising a transmitter and a receiver, each receiver comprising a plurality of energizing windings and a pivoted magnetic armature the angular position of which is controlled directly by the resultant flux generated by

said windings, two main and two auxiliary conductors constituting the sole connection between said stations, said main conductors being connected with a constant source of 5 alternating current and with some of the windings of each receiver, and each transmitter including means for setting up over a circuit comprising one of said main and one of said auxiliary conductors variable

alternating currents in the remaining windings of the receiver at the other station, whereby the resultant flux at each receiver may be modified as desired, and its armature shifted accordingly.

In testimony whereof we affix our signatures.
